UNITED STATES PATENT OFFICE.

KATE H. ATHERTON, OF CARSON CITY, NEVADA, AND MAE N. RODGERS, OF CHICAGO, ILLINOIS.

HOLDING DEVICE FOR TELEPHONE-RECEIVERS.

1,096,484.

Specification of Letters Patent.

Patented May 12, 1914.

Application filed May 24, 1913. Serial No. 769,665.

To all whom it may concern:

Be it known that we, KATE H. ATHERTON and MAE N. RODGERS, citizens of the United States, and residing, respectively, at Carson City, county of Ormsby, and State of Nevada, and the city of Chicago, county of Cook, and State of Illinois, have invented certain new and useful Improvements in Holding Devices for Telephone-receivers, 10 of which the following is a specification.

This invention relates to improvements in holding devices for telephone receivers and the object of the invention is to provide a simple device which may be connected to 15 any telephone stand for holding the receiver in such a manner that when the receiver is pulled forward into a convenient position for listening a switch lever of the telephone stand will be operated for closing the circuits in the usual way.

With the above object in view our invention consists in the features of invention, details of construction and combination of parts which will first be described in connection with the accompanying drawings and 25 then pointed out in the claims.

In the drawings,—Figure 1 is a view of a telephone set provided with our receiver holding attachment the parts being shown in 30 their position when the instrument is in circuit and ready for use; Fig. 2 is a similar view showing the receiver holding attachment swung around into idle or non-operating position the instrument in this position being out of circuit. Figs. 3 and 4 are similar views of another modification of our invention.

Referring to the drawings A is a clamping device arranged to engage the stand for 40 the purpose of supporting the attachment in the example now to be described where the attachment is to the ordinary portable stand. This clamping device conveniently consists of a split band or open ring provided with 45 ears a through which passes a screw a' provided with a nut whereby the band may be clamped to the stand. This clamping device has an arm a^2 to which is secured an upward extending post B. Upon this post is mounted 50 a tube C provided with an inclined or spiral slot c . To the post B is attached a radially arranged pin b which projects through the slot c . To the tube C is attached a receiver holding arm C' extending 55 at a suitable angle to said tube C and pro-

vided at its outer end with a clamping device D arranged to clamp and hold the telephone receiver. At an intermediate point on the tube C is loosely mounted a jaw device E pressing against a collar e secured to 60 the tube C above said jaw. This jaw device is provided with open jaws arranged to engage the ordinary fork of the receiver holding end of the switch lever F of the telephone set, a thumb screw e' being provided whereby the jaw device may be clamped to said switch lever. The slope of the slot c is such that the weight of the telephone receiver will tend to cause the tube C to slide down the post B and thereby rotate the tube C on said 70 post. In the extreme downward position of the tube C the receiver indicated at G is swung to one side in the position indicated in Fig. 2 and also the jaw device E is moved downward by the downward thrust of fixed 75 collar e , thereby carrying the switch lever downwardly to its lowest position against the action of the usual controlling spring or equivalent means tending to maintain the lever in its upper or closed circuit position, 80 whereby the subscribers' instruments are cut out of the circuit. When it is desired to bring the instrument into operation it is only necessary to catch the receiver and move it to a convenient position for listening, whereby 85 the tube C is rotated and owing to the inclined slot c' and pin b the said tube C is simultaneously elevated, thus allowing the outer end of the switch lever F to move upwardly and cut the instruments into the circuit. 90 As soon as the telephone receiver is released it tends to swing back to its inoperative position thus rotating the tube C and cutting out the subscribers' instruments.

The device illustrated in Figs. 3 and 4 is 95 constructed upon the same general principle as that shown in Figs. 1 and 2 but is intended for use with the ordinary wall set. In this case the clamping device instead of having an open ring or band is provided 100 with an open jaw arranged to clamp to any suitable part of the wall set and the arm C^2 instead of being attached to the top end of the tube C^3 passes through a slot in the same and is held by a screw indicated at c^2 . Furthermore, this arm is conveniently jointed 105 and provided with a clamping nut c^3 whereby the said jointed arm may be adjusted so as to hold the telephone receiver at a convenient position. The operation of this 110

modification is similar to that of the device shown in Figs. 1 and 2.

It will be noted that the device is simple and may be manufactured at a low price 5 while at the same time, since it does not embody the use of any springs, it is reliable in operation and not easily disarranged.

Having thus fully described our invention what we claim as new is as follows:

- 10 1. The combination with a telephone set having a transmitter, receiver and switch lever, of a post, means for holding said post in fixed relation to the transmitter support, a tube mounted on said post and provided with an inclined slot, a pin secured to the post and extending through said slot, a receiver holding arm attached to the tube, extending at an angle thereto and arranged to hold the receiver, means carried by the tube and arranged to clamp the end of the switch lever and mechanism carried by the tube for moving said means vertically but non-rotatably.
- 15 2. The combination with a transmitter, means for supporting the same, a receiver and a switch lever, of a clamping device ar-

ranged to be secured to the transmitter support, a vertical post carried by said clamping device, a tube mounted on said post and provided with an inclined slot, a pin secured to the post and extending through said slot, 30 a receiver supporting arm attached to the tube and extending at an angle thereto, a jaw device encircling the tube and provided with jaws arranged to engage the end of the switch lever and means carried by the tube 35 and arranged to hold said jaw device in fixed vertical relation to the said tube.

In witness whereof I have hereunto affixed my hand this 29th day of March 1913.

KATE H. ATHERTON.
